UNITED STATES PATENT OFFICE

WILLIAM E. WHITE, OF EVANSTON, ILLINOIS, ASSIGNOR TO KALMAN STEEL COMPANY,
OF CHICAGO, ILLINOIS, A CORPORATION OF DELAWARE

METHOD OF MAKING ROAD MATS

Application filed September 6, 1928. Serial No. 304,334.

My invention relates to the art of reinforcing concrete structures, and particularly to a method of manufacturing reinforcing fabric or mats for use in concrete roads.

The use of steel reinforcing in concrete roads is universal and the application of the steel in the form of a section of fabric is preferred. These sections of reinforcing material are called mats, and are formed by utilizing relatively small diameter deformed bars arranged in crossed relation and joined at the intersection of the respective crossed bars. Mats of this description are usually constructed to contain from 100 to 125 square feet of reinforcement, the bars being spaced from 12 to 24 inches apart in both directions.

The reinforcing mats as described may be conveniently assembled and fabricated in the shop but the problem of handling, shipping and transporting to the point of use, which is usually remote from the railroad, involves a substantial cost owing to the bulkiness of the articles and the care with which they must be handled in order to avoid distortion.

It is therefore highly desirable that the mats should be constructed in the field, that is, at the roadside adjacent to the point of use. The reinforcing rods may then be shipped in bundles and handled with ease with a substantial saving of cost. It has been proposed to do this by utilizing ties of different kinds such as heretofore suggested, but all such ties involve very serious objections. The simplest form of tie is a length of malleable wire

which is passed around the cross bars at each intersection and tied. Numerous forms of spring clips have also been suggested, the latter providing a somewhat insecure joint and involving fatiguing efforts on the part

of workmen. The same is true of the plain wire clips, which are wholly dependent for their stability on the degree of strength exerted by the workman.

An object of my invention is to provide a clip which shall be permanent in character,

rigid and firm beyond any possibility of separation by ordinary handling and which may be applied and secured in place by a single motion multiplied by a relatively long lever, thus reducing the effort required of the workman. Fundamentally, the idea is to construct a tie of relatively very stiff wire and entirely complete the tie except for one bending operation in an automatic wire machine. Another important requirement is that the tie shall be so constructed that the bending action necessary to complete it shall require a motion of less than 180 degrees for the following reason. The tie to be effective must be constructed of very stiff wire which necessitates the use of a lever in order to enable the workman to bend it. In mats of this character, the bars are relatively close together and any motion of more than 180 degrees with a lever of sufficient length is impossible due to interference with adjacent bars. Therefore, the tie must be so constructed that it may be formed in an automatic wire machine, applied in position and completed by a single short rotary movement. The wire, of course takes a permanent set and, due to its stiffness, serving as an efficient holding device for the crossed bars.

With a tie of this character available, the bars may be shipped to the roadside, laid out on an improvised form in proper spaced relation and the tie rapidly applied by the use of a simple tool. In this manner, one workman may manufacture the mats at the roadside as rapidly as the pouring of the concrete proceeds.

The method herein described will be more readily understood by reference to the accompanying drawings, in which

Fig. 1 is a perspective view showing a temporary holding rack or form with a plurality of reinforcing bars laid thereon;

Fig. 2 is an enlarged side elevation of the clip in its preformed condition, after it has been placed at the junction of two bars and

is ready for the application of the bending tool;

5 Fig. 3 is a view taken at right angles to that of Fig. 2 and showing the bending tool in its starting and finishing position and

Fig. 4 is a perspective view of a bending tool.

10 In the drawings, I have illustrated a simple rack or form consisting of side members 10 and end members 11 having notches adapted to receive the series of crossed bars A—B. The bars are held by a wire clip C and a bending tool is indicated at D.

15 The clip as best shown in Figures 2 and 3 is composed of a length of stiff wire of materially less diameter than that of the reinforcing bars or rods. The length of wire is doubled on itself to form a loop having a closed portion 12, a short leg 13 and a long leg 14. Preferably the two legs extend parallel to the extent of the length of the short leg, the long leg being continued and projected at an obtuse angle and terminating in a right angle bend or projection 15. Preferably also, 20 the extension of the long leg is laterally bent to extend part way around the bar B, all the described bending operations being done in an automatic wire machine. An essential however, is that the clip or tie shall be so 25 constructed that it may be placed in position at the intersection of two bars without distortion of the tie or bars. This is for the reason that the ties are necessarily formed of very stiff wire and must be so shaped that 30 they may be very easily placed in position by the use of the fingers only of the workman. When so placed, the ties will occupy the position shown in Fig. 2. Thereafter, a tool D having a straight body 16 and a notch 17 in the end thereof, is placed in the full-line position of Fig. 3. In that position, the hook or 35 projection 15 on the tie engages the body while the bifurcated end rests on the bar B. By the use of a simple tool of the construction shown, the bending force is exerted in a line coincident with the plane of rotation of the long leg around the bar; in other words, the force is not exerted eccentrically. This 40 is referred to in the appended claims as a simple movement. A rotary movement of less than 180 degrees, as indicated in Fig. 3, will serve to exert a powerful bending and binding action, the long leg 14 being bent into the dotted line position of Fig. 3. In 45 this position, the tie acts as a secure and permanent holding device.

50 Some of the steps of the described method may be varied without departure from the spirit of my invention, and I do not wish to 55 be limited except as indicated in the appended claims.

I claim:

1. The method of making road reinforcing mats, which consists in temporarily holding a 60 plurality of reinforcing bars in crossed rela-

tion, then completely forming stiff wire bar ties with the exception of one bending operation, the so formed ties being composed of wire of materially less diameter than of the bars, and shaped in such manner that they 70 may be applied to said crossed bars without distortion of the ties, then applying a tool to a free end of a tie, with a fulcrum on one of said bars, and, by a single rotary motion of less than 180 degrees, completing said tie 75 forming operation by bending said free end less than entirely around one of said crossed bars, and then repeating said tying operations at other intersections of said crossed bars.

2. The method of tying crossed bars for 80 road mats, which consists in bending a length of stiff wire of materially less diameter than the bars into a loop with one end materially longer than the other, then bending the loop 85 into U-shape, the tie in this condition being adapted to be formed by an automatic wire machine, and to be applied to crossed bars without distortion of the tie or bars, thereby 90 a single simple rotary motion, through less than 180 degrees, bending the long leg partly around one of the bars to complete the tie, the stability of the tie being dependent on the stiffness of the wire of the tie.

3. The method of tying crossed bars for 95 road mats, which consists in bending a length of stiff wire of materially less diameter than the bars into a loop with one end materially longer than the other, then bending the loop 100 into U-shape, the tie in this condition being adapted to be formed by an automatic wire machine and to be applied to crossed bars without distortion of the tie or bars, then by a single rotary motion, bending the long leg around one of the bars to complete the tie, 105 the stability of the tie being dependent on the stiffness of the wire of the tie.

4. The method of tying crossed bars for 110 road mats, which consists in bending a length of stiff wire of materially less diameter than the bars into a loop with one end materially longer than the other, and terminating in a projection acting as an abutment for a tool, then bending the loop into U-shape, the tie 115 in this condition being adapted to be formed by an automatic wire machine and to be applied to crossed bars without distortion of the tie or bars, then engaging the abutment on said long leg with a tool with a fulcrum on a bar, and then by a single simple rotary motion, bending the long leg around one of the bars to complete the tie, the stability of the tie being dependent on the stiffness of the wire of the tie.

5. The method of tying crossed bars for 120 road mats, which consists in bending a length of stiff wire of materially less diameter than the bars into a loop with one end materially longer than the other, and terminating in a projection acting as an abutment for a tool, 125

130

then bending the loop into U-shape, the tie in this condition being adapted to be formed by an automatic wire machine and to be applied to crossed bars without distortion of the tie or bars, then engaging the abutment on said long leg with a tool with a fulcrum on a bar, and then by a single simple rotary motion through less than 180 degrees, bending the long leg partly around one of the bars to complete the tie, the stability of the tie being dependent on the stiffness of the wire of the tie.

In testimony whereof he has affixed his signature.
